UNITED STATES PATENT OFFICE.

MARTHA K. SCHAUER, OF DAYTON, OHIO.

DRAWING-TABLE.

1,338,254.

Specification of Letters Patent. Patented Apr. 27, 1920.

Application filed May 7, 1919. Serial No. 295,270.

To all whom it may concern:

Be it known that I, MARTHA K. SCHAUER, a citizen of the United States, residing in the city of Dayton, county of Montgomery, 5 and State of Ohio, have invented certain new and useful Improvements in Drawing Tables, of which the following is a specification.

This invention relates to new and useful 10 improvements in drawing tables.

The principal object of the invention is to provide a drawing table containing vertically-movable means that serve not only as copy-holders, but as partitions which divide 15 off the table for the accommodation of two or more students. The space on each side of a partition becomes, in a sense, a separate table for each student. My improved tables are therefore well adapted for any school 20 in which drawing or kindred instruction is given.

Another object of my invention is to provide shelves that may be readily attached, if desired, to the top portions of the table 25 partitions.

Other important and incidental objects will be brought out in the following specification, and particularly set forth in the subjoined claims.

30 The different forms of embodiment of my invention are illustrated in the accompanying drawings, of which Figure 1 is a front view of one of my improved drawing tables equipped with three vertically-movable partitions. Fig. 2 is a top view of said table. Fig. 3 is an end view thereof. Fig. 4 is a front view of a table equipped with a rear copy-holding board. Fig. 5 is a top view 35 thereof. Fig. 6 is a side view of the same. Fig. 7 is a detail end view of one of the copy-holding boards, showing a shelf supported thereby and the means for holding the board in its raised position above the table top. And Fig. 8 is a side view of said 40 copy-holding board, shelf and holding means.

Throughout the specification and drawings, similar reference characters denote corresponding parts.

45 Referring to the accompanying drawings, the numeral 1 designates a flat table top supported by legs 2. The table is shown as elongated in Figs. 1, 2 and 3, with three longitudinal slots 3, 4 and 5 provided on a middle line running lengthwise of the top 1. Vertically movable through each slot 3,

4 and 5, to a position either above or below the table top 1, is a copy-holding board 6. In its position below the top surface of the table top 1, each board 6 rests upon a longitudinal rail 7 connected between end rails 8 that are secured between each end pair of legs 2. Grooved guides 9 extend from the bottom rail 7 to the table top 1, to receive the boards 6 for the purpose of guiding them during their up and down movement. (See Figs. 1 and 3.)

In Figs. 1, 2 and 3, the copy-holding boards 6 are shown in their positions under the table top 1, whereby the table is free to be used as any other one which is adapted for general use. Now, when it is desired to use the table as one that will accommodate a group of drawing students—let us say six in the present instance—the boards 6 are drawn upwardly through their respective slots until they reach their uppermost positions. For the purpose of holding these boards in their raised positions, there is provided in the lower end edges of each one a recess 10 that receives the knee-shaped end 11 of a spring catch 12. As soon as the boards 6 are raised to their normal upper positions, the ends 11 of the catches 12, being under no further restraint, are pressed 70 outwardly above those portions of the table top 1 at the ends of the slots to support said boards in their elevated positions. When it is desired to lower the boards 6, the ends 11 of the catches 12 are pressed inwardly a sufficient distance to clear the slot edges to permit the boards to descend to their normal positions below the top 1. While I employ this form of catch, any other type may be used for this purpose 75 without departing from the spirit of the invention.

When the boards 6 are held in their elevated positions, they not only serve as means for holding a copy or model for the student 80 on each side of it, but they act as partitions to divide off the table into separate spaces for the accommodation of numerous students. This feature of my invention commends itself particularly to drawing and other art schools, by providing ample and efficient table space for the students without involving the expense of furnishing a separate table for each student.

85 Referring to Figs. 7 and 8, it will be seen that a shelf 13, may, if desired, be attached 90 by brackets 14 or other suitable means to

the top of each vertically-movable board 6, to support models or other articles used by the student or teacher.

Between the guides 9 a drawer 15 is provided to receive the working tools and material of the students who are assigned to the table for their drawing work. It will thus be seen that in the instance described, one table may be easily transformed into six 10 separate drawing tables by raising the three partition boards 6.

In Figs. 4, 5 and 6, I have illustrated a small table provided with a copy-board 6 adapted to be raised through a slot located 15 near the end edge of the top 1. In these figures the board is shown in an elevated position.

On each side of the copy-board 6, near its top portion, there is provided a concave recess 16 for the fingers by means of which the board may be firmly gripped for the purpose of raising it. These boards may also act as background areas for groups of objects that might be arranged for students 25 of drawing, since draperies and other background materials can be pinned against them. Such groups can be placed on each side of a raised board, thus affording six individual drawing subjects, as shown by the 30 table in Fig. 2. Objects on one side of the table can be used by the students in one class and those on the other side by a class immediately following. This saves time, energy and confusion.

35 I do not wish to be limited to the details of construction and arrangement herein

shown and described, and any changes or modifications may be made therein within the scope of the subjoined claims.

Having described my invention, I claim: 40

1. In a drawing table, the combination with a top therefor containing on a line running lengthwise through its middle portion, a series of elongated slots, of copy-holding boards vertically movable through 45 said slots to positions above the top that divide it into separate drawing spaces, means below the top on which said boards rest in their lower positions, and guides for said boards between said top and supporting means.

2. In a drawing table, the combination with a top therefor containing on a line running lengthwise through its middle portion, a series of elongated slots, of copy-holding boards vertically movable through 55 said slots to positions above the top that divide it into separate drawing spaces, a pair of legs supporting each end of said top, an end rail connected between the lower 60 ends of each pair of legs, a longitudinal rail connected to the middle portions of said end rails, to form a support for said boards in their lowermost positions, and grooved guides extending between said longitudinal 65 rail and table top, to receive said boards.

In witness whereof I have hereunto set my hand this 5th day of May, 1919.

MARTHA K. SCHAUER.
